United States Patent Office.

AVERY DENISON, OF WOODVILLE, OHIO, ASSIGNOR TO HIMSELF
AND WILLIAM KEIL, OF SAME PLACE.

Letters Patent No. 95,096, dated September 21, 1869.

IMPROVEMENT IN APPARATUS FOR MAKING BUTTER.

The Schedule referred to in these Letters Patent and making part of the same

To whom it may concern:

Be it known that I, Avery Denison, of Woodville, Wood county, Ohio, have invented a new and useful Improvement in Implements for Making or Working Butter from Cream; and I do hereby declare the following to be a full, clear, and exact description of the same, reference being had to the accompanying drawings, and to the letters and figures thereon, which are hereby made a part of this specification.

Figure 1 represents in perspective a view of my improved butter-worker complete.

Figure 2 represents a cross-section of the same.

Figure 3 represents the inner surfaces of the cylinder B, in two parts, when detached, showing the grooves or furrows of the same.

Figure 4 represents the obverse side of the cylindrical wheel or drum C, which plays within the cylinder B, and shows the grooves and pinions of the same. The inverse side corresponds thereto.

Figure 5 represents the geared wheels D and E.

Figure 6 represents the journal-box H.

The same letters indicate like parts in all the figures.

This invention relates to that class of dairy-utensils used for making or working butter from cream, and is designed to use friction in accomplishing the breaking of the globules of the cream.

A represents the table or support of my improved butter-worker.

B represents the cylinder, which is composed of two parts, and is supported upon the table or support A by the projections a a a a.

The two parts are fastened together by means of the governors or clamps b b b.

c' is the upper orifice, made to receive a funnel into which the cream is poured.

c" is the lower orifice, one-third the size of the upper orifice c', where the cream, when the globules are broken, is discharged.

d is an opening in one part of the cylinder, to receive the shaft g of the geared or pinion-wheel E.

Around this opening d is the plane surface d', as shown in the drawing, and is designed, in connection with a similar plane surface on the other part of the cylinder, and upon both sides of the grooved wheel or drum C, to prevent the grooves or furrows of the same from coming in close contact.

The inner surfaces of the two parts of the cylinder are grooved or furrowed, which furrows or grooves are arranged in conic sections, and diverge from the centre to the circumference, extending from the plane surface d' to the circumferential rim d", as shown in the drawings. These grooves or furrows are cut or formed vertical on one side, and the hollowed portions diverge to the straight line at an angle of about forty-five degrees.

C is a cylindrical-shaped wheel or drum, of a uniform thickness transversely, its obverse and inverse sides having grooves or furrows corresponding to those of the inner surfaces of the cylinder B. The bevelled

edges of this wheel or drum are furrowed or milled similar to coin.

D is a geared wheel supported upon the gudgeon e, and secured thereon by the pin e'.

f is the handle or arm of the same.

E is a pinion-wheel, which meshes into the geared wheel D.

g is the shaft of the same, its journal resting in the box H. This shaft g passes through the opening d in one part of the cylinder B, and carries the grooved wheel C, which plays in the cylinder.

To use my improved butter-worker, the cylindrical wheel C is placed within the cylinder B, the parts of which are then securely fastened together by means of the clamps b b b, and the cylinder placed in the opening of the table or support A, and rests upon the projections a a a a. The shaft g of the pinion-wheel E is geared through the opening d, and the core of the cylindrical wheel C which it carries. The journal of the shaft g rests in the box H, upon the table A. The geared wheel D is placed upon the gudgeon e, and secured by the pin e', and meshed into the pinion-wheel E, motion being given to the whole by means of the handle or arm f.

The cylindrical wheel C should be placed upon the shaft g, so that the vertical sides of the furrows will be in opposition to those of the inner surfaces of the cylinder B, so as to cut or break the globules of cream in its revolutions, until the cream is reduced to a pulp or uniform mass, and being swept by the wheel, in its motion, over the landings of the grooves in the cylinder-wheel to the lower orifice c', whence it escapes into a vessel, and is transferred to a dasher-churn for the purpose of further agitation, and gathering the particles of butter together.

What I claim, and desire to secure by Letters Patent, is—

1. The arrangement of the two parts of the cylinder B, projections a a a a, governors or clamps b b b, upper orifice c', lower orifice c", opening d, the grooves or furrows in its inner surface, plane surface around the opening d, when constructed and operating substantially as herein set forth.

2. The arrangement of the cylindrical wheel C, plane surface of the same, c", around the opening or core made to receive the shaft g, with the arrangement of the grooves or furrows, as shown in the drawings, when constructed and operating substantially as herein described.

3. The geared wheel D, gudgeon e, pin e', handle f, pinion-wheel E, shaft g, box H, when constructed, arranged, and operating substantially as herein specified.

4. The combination and use of the table A, cylinder B, cylindrical wheel C, geared wheel D, pinion-wheel E, box H, with their attachments, as herein specified, when constructed, arranged, and operating substantially as and for the purposes mentioned.
